BLOCK PLANE

Raymond P. Lavietes, Shelton, Conn., assignor to
Abraham H. Lavietes, Shelton, Conn.

Application November 9, 1944, Serial No. 562,671

2 Claims. (Cl. 145—14)

1

This invention relates to carpenter's planes, particularly block planes, and has for an object to provide an improved and simplified construction in which there is a solid support for the blade independent of the working parts or adjusting means.

It is also an object to produce a more solid construction which provides more solid support for the blade and eliminates chattering, and in which the blade is much less apt to shift or work out of position in use.

A further object is to provide a construction in which the weight or pressure of the blade is on a part of the actual body or base rather than on the working or adjusting mechanism for the blade, with the result that wear on working or adjusting parts is greatly reduced.

A still further object is to combine with such a support a positive drive from the adjusting means to the blade in which there is nothing to wear out or slip, and it is so arranged that when the parts are assembled the adjusting mechanism is properly and positively connected to the blade, and which construction is also so arranged that the clamping cap cannot be placed in position unless the adjusting means is properly connected to the blade, and, therefore, there is no danger of the blade being clamped if it is not properly connected to the adjusting means, which might otherwise allow the blade to slip out of place in use.

With the foregoing and other objects in view I have devised the construction illustrated in the accompanying drawing forming a part of this specification. It is, however, to be understood the device is not limited to the specific details of construction and arrangement shown, but may embody various changes and modifications within the scope of the invention.

In these drawings:

Fig. 1 is a top plan view of the plane;

Fig. 2 is a longitudinal section substantially on line 2—2 of Fig. 1;

Fig. 3 is a top plan view with the clamp or cap removed, and

Fig. 4 is a top plan view of the blade and the lateral adjusting means.

This improved plane comprises a metal body or base 5 having the usual bottom wall 6 and the upright side walls 7, the bottom wall being provided with the usual transverse slot 8 through which projects the cutting edge 9 of the blade 10. The rear edge wall of this slot is preferably beveled as shown at 8a to form a seat for the blade. As in the usual arrangement, the blade

2

must be supported in an inclined position at the proper angle with the cutting edge properly located in the slot and the bevel 11 at the proper angle. In this construction an improved supporting means is provided for the opposite end portion of the blade which supports this blade directly on the body or base and independently of the adjusting means for the blade. This support, indicated at 12, comprises a metal strip, in this case a strip of substantially flat metal, offset upwardly to form a looped portion provided with a top wall 13 upon which the blade rests, this looped portion being preferably of substantially inverted U-shape, thus forming upright supporting walls 14 and 15 for the substantially flat top wall 13. The lower end of the wall 14 extends laterally to provide a supporting foot 16 resting on and secured to the bottom wall 6 of the body or base by any suitable means, preferably welding, and the extension of the forward wall 15 also extends over the wall 6 and is secured thereto by similar means, preferably at the portion 17. This portion 12, however, is somewhat longer than the portion 16 so as to provide a support or mounting for a combined securing means for the blade clamp and a lateral adjustment for the blade, indicated at 18.

The blade is provided with an opening 19 and the supporting top wall 13 is provided with a longitudinal slot 20 through which projects a lug 21 from an adjusting block 22 threaded on an adjusting screw 23 mounted in the support below the top wall 13. This screw in the present case is mounted in the upright walls 14 and 15 and may be held against longitudinal movement by any suitable means, such for example as reduced end portion 24 and a securing washer or cotter 25. It has a knurled knob 26 for easy manipulation, and it will be seen that when the blade is not clamped operation of the screw will adjust the blade longitudinally. It will be evident with this construction there is a positive drive from the adjusting means to the blade in which there is no danger of relative slipping between the two and there is nothing to wear out, so that this positive connection will be maintained indefinitely.

Mounted above the blade is the cap or clamp 27 which is an elongated member arranged with its forward end portion 28 resting on the top of the blade adjacent the cutting edge, and at its opposite end portion is curved or convexed to form a sort of semi dome-shaped grip 29 which is so shaped as to comfortably fit the palm of the operator's hand and form a good grip by which the proper pressure or force may be applied

in using the plane. Mounted in this cap or clamp is a clamping screw 30 which includes a knurled operating knob 31 above the clamp, and which passes through the clamp so that its lower end presses against the top of the blade 10 to firmly clamp this blade against the top wall 13 of the rigid support 12. There is preferably a clamping head 32 on this end of the screw and loosely mounted thereon so that it may seat properly on the blade and also will permit the screw to turn relative thereto, so that this clamping end is not apt to turn on the blade and wear depressions or recesses therein or mar the surface of the blade.

Forwardly of the screw the clamp is provided with a keyhole-shaped opening 33 through which the member 18 projects. This member is secured at 34 to the forward portion of the support member 12 for turning movements thereon, and includes an eccentric 35 passing through an elongated slot 36 in the blade and engaging the side walls of this slot. Above this eccentric this member has a flange 37 forming a shoulder to rest on the top of the clamp 27 and prevent upward movement under action of the clamp screw 30. The wider portion of the keyhole shaped opening 33 is of a size to permit this flange to pass through, but the narrower portion of the opening 33 is of less width than the diameter of this flange so that it cannot pass through it, and when the clamp is in the position shown in Figs. 1 and 2 with the reduced portion 38 in the narrow portion of this opening 33 the clamp will be held in position by the flange 37. The upper end portion of the member 18 is bent laterally to form a grip 39 for operating it.

An auxiliary hand grip 40 may be mounted on the forward end of the lower wall 6, and the side walls 7 may be provided with an opening 41 to receive the thumb and a finger to improve the grip.

It will be seen that with this construction tightening of the screw 30 will clamp the blade firmly on the top wall 13 of the support, which support is a solid support firmly mounted directly on the body or base 5. The blade is therefore directly and solidly supported on the base and entirely independently of the adjusting means for the blade. Therefore, there is no unusual wear on the adjusting means, and there is much more solid and rigid support for the blade than where the blade is carried by the adjusting means or other working parts. The eccentric 35 cooperating with the sides of the elongated slot 36 in the blade forms a convenient means for shifting the cutting edge of the blade laterally to adjust it in the slot 8 to insure its being located parallel to the bottom wall of the base to secure uniform cutting. It will also be seen that the collar 37 forms a fulcrum for the clamp or cap 27, so that when the clamping screw 30 is tightened the forward end portion 28 of the clamp firmly clamps the forward end portion of the blade against the bottom wall 6. The solid clamping of the blade against a solid immovable support eliminates chattering of the blade, and also so holds and supports it that there is very little danger of its shifting or moving out of position in use. It will also be seen that the positive connection from the adjusting means to the blade comprising the lug 21 seating in the opening 19 in the blade insures that the blade must be properly located with this lug in the opening, and therefore the adjusting mechanism properly and positively con-

nected to the blade, before the cap 27 can be placed in position. There is, therefore, no danger of this cap being assembled and the blade being clamped if it is not properly connected to the blade adjusting means, which might otherwise permit the blade to slip out of place in use. It will of course be understood that after loosening the clamp 30 the blade may be readily adjusted longitudinally to the desired position by manipulating the screw 23. After the blade is thus properly located the cutting edge 9 may be lined up with the slot 8 and the surface of the lower wall of the base by turning the eccentric 35, which will shift the forward end of the blade and the cutting edge laterally by swinging the blade about the lug 21 as a pivot, after which the screw 30 may be tightened to securely clamp all the parts in their proper positions. On the other hand, the clamp 27 and the blade may be readily removed for sharpening or renewal of the blade by merely loosening the screw 30, which will permit the cap 27 to be shifted backwardly or to the right to bring the flange 37 into alignment with the wider portion of the keyhole shaped opening 33, which will permit the clamp 27 to be then lifted from the device, and then the blade 10 may also be merely lifted from the device.

Having thus set forth the nature of my invention, what I claim is:

- 30 1. A plane of the character described comprising a base having a transverse slot, a blade inclined to the base having a cutting edge adapted to project through said slot, a support for the blade mounted on and secured to the base comprising a metal strip including an inverted upwardly extending looped portion providing a top wall on which the blade rests and which is provided with a longitudinal slot, an adjusting means mounted in said looped portion below the top wall including means projecting through the slot in the top wall connected with said blade for adjusting it, a cap over the blade connected with the base, and a clamping screw carried by the cap for clamping the blade to said top wall.
- 35 2. A plane of the character described comprising a base having a transverse slot, a blade inclined to the base having a cutting edge adapted to project through said slot, a support for the blade mounted on the base comprising a substantially flat strap of metal extending longitudinally of the base including an inverted substantially U-shaped portion forming a top wall on which the blade rests, said strap also including supporting feet extending in opposite directions from the lower ends of the side walls of the U-shaped portion fastened to the base, an adjusting means mounted in said support and including means connected with the blade to adjust the blade on the support, and a clamp above the blade including means for clamping the blade against said top wall.
